UNITED STATES PATENT OFFICE.

DANIEL H. THOMAS AND EDWARD A. SCHAMBS, OF WICHITA FALLS, TEXAS.

PUMPING JACK.

Application filed January 31, 1927. Serial No. 164,900.

This invention relates to tools and equipment for pumping wells and it refers particularly to an improvement in pumping jacks, its principal object residing in an attachment for such a jack by which to establish positive vertical movement of the beam at its point of engagement with the polished rod, to insure against excessive side draft upon the rod, resulting in premature wearing.

10 In pumping jacks of the usual construction, the beam in its travel describes an arc at its point of engagement with the polished rod, and since this engagement is more or less positive as regards the lateral displacement of the rod, the latter is constrained to follow the movements of the beam, and thus deviate from the vertical plane of travel which is deleterious in the effect mentioned above, and it is the purpose of the present invention to obviate this apparent disadvantage and produce a device of considerable efficiency, at a nominal cost.

With these foremost objects in view, certain other features of construction and arrangement of parts will become apparent as the description proceeds, taken in connection with the accompanying drawings, wherein:

Figure 1 represents a side elevational view 30 of a jack equipped with the present invention.

Figure 2 is a modified example of the invention and its method of installation at a different location on the jack, and

35 Figure 3 is a further modification of the invention illustrating a hinge connection between the beam and supporting post.

It may be stated in continuing further in detail, that arcuate cams, slotted plates and similar devices have preceded the present invention in purpose, but disadvantages have been found to exist in numbers of these movements in that some depend upon the jack for their compensating movement, while others, being dependent upon a slot and pin, or are frequently slid suddenly from the rectilinear path, due to unwarranted wear, often subject the rod to sudden lateral stresses. It is the object of the present invention to provide in addition to slot defining a changing curve, a co-operative straight slot, with a sliding pin, functioning to restrain movement of the beam in lateral directions during its rectilinear travel.

55 Referring now more closely to the drawings, the frame of the jack constitutes a base

member 1, and an upright supporting post 2, also an oblique brace 3. The angle or V 4 is operative upon a bearing 5 mounted upon the base member 1, and has pivotal engagement through a bar 6 with the beam 7. Operation of the V 4 is established in the usual way by engagement of the line 8 with the stirrup 9 situated near the end of the upright portion of the V.

Taking first the Figure 1 of the drawings, the invention forms the connection between the beam 7 and post 2, there being as a result, a limited lateral displacement of the beam accordingly with its vertical pivotal movement such lateral displacement being controlled and restricted entirely by the pivotal displacement of the plate 10, by reason of the pin 11 following the curve of the slot 12, co-incident with the horizontal sliding 75 of the slot 13 upon the pin 14. It is evident that the restricted position of each of the pins 11 and 14 prevent displacement of the plate in excess of the required amount sufficient to produce an arcuate movement 80 at the operative end of the beam.

In Figure 2, while a slight departure in form is apparent, the general plan is adhered to and the result identical. The pins 11 and 14 are formed integral with a bracket 15, 85 which is bolted upon the polished rod 16. Instead of utilizing the plate 10, only a skeleton frame is employed, as shown, defining slots 12 and 13 similar to those made in the plate. At the lowest position of the beam in pumping, the pin 14 occupies a position in slot 13 remote from the arcuate slot 12, while the pin 11 moves to the top of the arcuate slot, such positions being reversed upon upward movement of the beam.

A still further modification of the invention is apparent in Figure 3. This figure illustrates the beam 7 as being connected to the post 2 by links 17 forming a kind of hinge. The beam is thus free to move in a lateral direction as well as vertically, and the invention which in the present case is bolted to the post 2, controls either movement of the beam by the pin and slot arrangement shown, that is, by constraining the operative end of the beam in a rectilinear line of travel. This latter modification however like the others previously described in function, is devoid of the lateral slot 13, containing only the arcuate slot 12 in which 110 moves the pin 11 carried by the beam 7.

Manifestly, the construction shown is capa-

ble of considerable variation, and such variation as is in keeping with the appended claims is considered within the spirit of the invention.

5. What is claimed is:

1. A device of the character described comprising in combination with a pumping jack, a plate having an arcuate opening at one end, and an elongated opening situated 10 at right angles to said first opening; said plate being secured to the beam of said jack; and pins arranged stationary with respect to the mounting of said beam to operate in said openings to restrict and co-ordinate 15 the vertical and lateral displacement of said beam.

2. A device of the character described comprising in combination with a pumping jack, a member in which is formed right 20 angular slots, one of which is arcuately curved; said member being arranged rigid with respect to the beam of said jack, and means arranged stationarily relative to the mounting of said beam and operable in said 25 slots to displace the pivotal point of said beam and to restrict said displacement in accordance with the vertical travel of said beam.

3. A device of the character described 30 comprising in combination with a pumping jack a member having a curved slot therein carried by the beam of said jack, means

operable within said slot to permit of displaced pivotal movement of said beam, and means adjacent said curved slot to restrict 35 such displacement and to constrain the operative end of said beam to move in a rectilinear path.

4. A device of the character described comprising in combination with a vertically 40 actuated beam; a member carried by the beam formed to define a curved slot; means operable within said slot to permit of vertical pivotal movement of said beam; means on said member to restrict said movement 45 and to permit of limited lateral displacement of the pivotal point of said beam to constrain the operative end of said beam to move in a rectilinear path.

5. A device of the character described 50 comprising in combination with a vertically actuated beam; a member carried by one end of said beam for mounting the latter, said member having a curved slot therein; a pin operable in said slot to permit said beam to 55 pivot vertically thereon; means in said member to restrict such movement and to constrain the operative end of said beam to move in a strictly vertical plane.

In testimony whereof we affix our signatures.

DANIEL H. THOMAS.
EDWARD A. SCHAMBS.
